UNITED STATES PATENT OFFICE.

ISAAC W. ALLYN, OF PHILADELPHIA, PENNSYLVANIA.

PEN WIPER AND HOLDER.

SPECIFICATION forming part of Letters Patent No. 331,270, dated December 1, 1885.

Application filed December 2, 1884. Serial No. 149,306. (No model.)

To all whom it may concern:

Be it known that I, ISAAC W. ALLYN, a citizen of the United States, residing at Philadelphia, in the county of Philadelphia and State 5 of Pennsylvania, have invented certain new and useful Improvements in Pen Wipers and Holders; and I do declare the following to be a full, clear, and exact description of the invention, such as will enable others skilled in the 10 art to which it appertains to make and use the same, reference being had to the accompanying drawings, and to the letters and figures of reference marked thereon, which form a part of this specification.

15 My invention relates to improvements in pen wipers and holders, having for its object to provide a receptacle adapted to receive and retain a pen and prevent the same from corroding; and the invention consists in the construction and combination of parts substantially as hereinafter fully described, and pointed out in the claims.

20 In the drawings hereto annexed, Figure 1 is a plan view of a combined inkstand and holder, and Fig. 2 is a side elevation thereof. Figs. 3, 4, and 5 are detail views of the bristles arranged in a bunch and provided with securing and contracting bands.

25 Referring to the drawings, in which like letters of reference indicate like parts in all the figures, A designates the base or bottom plate of an inkstand having ink-wells or receptacles B B made integral therewith or separate therefrom.

30 The base-plate and ink-wells are of any preferred design or material, said ink-wells being provided with covers or stoppers B' B', as is usual.

35 C designates a holder or receiver, preferably arranged between the ink-wells, and made integral with or separate from the base-plate A thereof, as may be desired. Within the receiver C, I place a bunch of bristles, D, cemented, glued, or otherwise securely held together at their base, the upper ends thereof being free and filled with a powdered non-corrosive substance. At the base of the bristles D, I place a band, E, of tin or any other preferred material, which surrounds the said

bristles and serves to more securely hold the 50 same together.

F designates a similar band of slightly greater diameter than the band E, as shown in Fig. 5, over which it fits and is adapted to slide. In Fig. 3 the band F is of the same 55 diameter as the band E.

The dotted lines in Figs. 3 and 5 show the band F in a more elevated position than it is represented in full lines.

I sprinkle a finely-powdered substance in 60 between the bristles, which will prevent a pen from corroding—as, for instance, talc, which I find unobjectionable and gives entire satisfaction.

I attach importance to the bristles arranged 65 in a bunch and supplied with talc in a finely-powdered state, and provided with means for securing the bristles together.

70 By reference to Figs. 2, 3, and 5 of the drawings it will be seen that the bristles are so cut and arranged as to present an oval top surface, which I find to be very useful.

In practice I make the stoppers B' tapering, and form the necks of the ink-wells similar in shape to cause said stopper to fit tightly there- 75 in and prevent the escape of ink when the ink-well is overturned.

I am aware that various modifications in the form and proportion of parts can be made 80 without departing from the spirit or sacrificing the advantages of my invention, the essential features of which will be readily understood from the foregoing description.

In order to render the device more effective, it is desirable that the pen be first cleaned or 85 wiped on the bristles before placing it in the holder—that is, standing it in the bristles in a vertical position.

Having thus fully described my invention, what I claim, and desire to secure by Letters 90 Patent, is—

1. In a pen wiper and holder, the combination of a bunch of bristles cemented or glued together at the bottom thereof, a band surrounding said bristles at the base, and an adjustable band, substantially as and for the purpose set forth. 95

2. As a new article of manufacture, a pen

wiper and holder consisting of a suitable receptacle, a bunch of bristles cemented or glued together at the bottom thereof and supplied with tale in a finely-powdered state, a
5 band inclosing said bristles at the base thereof, and an adjustable band adapted to slide upon said bristles, as and for the purpose set forth.

In testimony whereof I affix my signature in presence of two witnesses.

ISAAC W. ALLYN.
